Primary Examiner — Marissa J Cash*Assistant Examiner* — Altaira J Swangin(74) *Attorney, Agent, or Firm* — Price Heneveld LLP(57) **CLAIM**

I claim the ornamental design for a handle, as shown and described.

DESCRIPTION

FIG. 1 is a front perspective view of a handle of the present disclosure;

FIG. 2 is a front elevational view of the handle of FIG. 1; FIG. 3 is a rear elevational view of the handle of FIG. 1; FIG. 4 is a first side elevational view of the handle of FIG. 1;

FIG. 5 is a second side elevational view of the handle of FIG. 1; FIG. 6 is a top plan view of the handle of FIG. 1; and, FIG. 7 is a bottom plan view of the handle of FIG. 1. The broken lines depict portions of the article that form no part of the claimed design.
